CLAIM

The ornamental design for a wheel alignment target body, as shown and described.

DESCRIPTION

FIG. 1 is a front perspective view of the wheel alignment target body;

FIG. 2 is a rear perspective view of the wheel alignment target body;

FIG. 3 is right side plan view of the wheel alignment target body;

FIG. 4 is top plan view of the wheel alignment target body;

FIG. 5 is a left side plan view of the wheel alignment target body; and,

FIG. 6 is a bottom side plane view of the wheel alignment target body.

Broken lines, if any, shown within the drawings illustrate features that form no part of the claimed design.
